UNITED STATES PATENT OFFICE.

WILLIAM JAMES NOTT, OF WEST CROYDON, SOUTH AUSTRALIA, AUSTRALIA.

PUMP VALVE.

1,406,885.

Specification of Letters Patent. Patented Feb. 14, 1922.

Application filed August 25, 1920. Serial No. 405,985.

To all whom it may concern:

Be it known that I, WILLIAM JAMES NOTT, a subject of the King of Great Britain and Ireland, residing at Franklin Terrace, West 5 Croydon, State of South Australia, Commonwealth of Australia, have invented certain new and useful Pump Valves, of which the following is a specification.

This invention comprises certain improvements in pumps for lifting water and other liquids, and in particular it relates to the construction of the valves and the seatings therefor and to the construction of the plunger and the fitting of the bucket 10 leathers thereto.

According to my invention the valve seatings, that of the foot valve and that of the plunger valve, instead of being square across the barrel of the pump, are formed obliquely 20 or at an angle thereto; and in addition the plunger is fitted, immediately below the valve, with two bucket leathers one above the other each being held in place by a back nut.

25 In order that my invention may be the more clearly understood I will describe the same with reference to the accompanying drawings in which—

Fig. 1 is a vertical central section of a 30 pump barrel showing an external side view of the foot piece and of the plunger, with their respective valves in place therein.

Fig. 2 is a front view of the plunger and valve.

35 Fig. 3 is a vertical central section of the plunger and valve on line *a b* of Fig. 2.

Fig. 4 is a front view of the foot piece and valve.

40 Fig. 5 is a vertical central section of the foot piece and valve on line *c d* of Fig. 4.

Fig. 6 is a plan view of the plunger and valve and

Fig. 7 is a plan view of the foot piece and valve.

45 Figs. 8 and 9 are views in elevation of a fishing tool useful in the removal and insertion of the valve.

The barrel *A* is made of a length of pipe, preferably of brass. Screwed upon its lower 50 end is a collar *B* which has a central screw-threaded portion to take the bottom of the foot piece and a bottom screw-threaded portion to take a piece of suction pipe of any required length, not shown in the drawings.

55 Screwed upon its upper end is a collar *C* which has an upper screw-threaded portion

preferably of somewhat greater diameter whereby it is secured to the bottom end of the delivery pipe which may be made up of any number of pieces to give the required 60 depth, and the upper end of which is secured at the top of the well.

The foot valve *D* is carried by a short tubular foot piece *E* having a screwthreaded bottom end whereby it is held in place as 65 above described and an oblique upper face or seating *F* for the valve.

The valve *D* consists of a flat approximately oval shaped metal back having a face of more or less resilient material such 70 as leather, rubber or softened copper attached thereto to fit closely upon the valve seating. The lower end of the valve *D* is supported and rests upon a narrow shoulder *G* formed in the foot piece at the base of the 75 valve seating. To hold it central relatively to the valve seating it has a notch *H* in the centre at the bottom end and another notch *J* in the centre at the top end. The bottom notch is engaged by a short pin or stud *K* 80 projecting from the valve seating at the centre of the shoulder *G*, and the top notch is engaged by a longer and slightly curved pin or stud *L* projecting from the upper edge of the valve seating across the water 85 space towards the opposite side of the barrel.

The plunger valve *M* is constructed and controlled in the same way as the foot valve *D*, the plunger *N* being made in the form of a tube with two leathers around its lower 90 portion, a screwthreaded socket *O* at the top for attachment to the pump rod, and an oblique upper face or seating *P* for the valve *M*. The valve is supported and rests upon a shoulder *Q* and is maintained in central 95 position relatively to the seating by pins or studs *R* and *S*.

The plunger is fitted with two leathers *T*, each of which is held in place by a back nut *V*. Each of the leathers *T* is in the form 100 of a short cylinder with its two ends slightly bevelled off, the inner edge being cut away at the top and the outer edge cut away at the bottom. Each of the nuts *V* has its inside upper edge cut away to form a shallow cup 105 to hold the bottom of the leather. The fitting is as follows:—The bottom portion of the plunger *N* is reduced somewhat in diameter and is externally screwthreaded for a length approximately equal to the height of 110 the two bucket leathers *T* and the two nuts *V*. The upper leather is first placed upon the

plunger and moved up to its working position, that is almost to the top of the reduced portion. The upper back nut is then screwed upon the plunger, its cup-shaped upper edge 5 impinging upon and forcing the bottom portion of the leather into the threads of the plunger and so holding it in place. The second leather is then passed upward over the threaded portion of the plunger until its 10 top edge almost meets the bottom of the upper nut. The second back nut is then screwed upon the plunger, its cup-shaped upper edge forcing the bottom portion of the leather into the threads of the plunger and 15 so holding it in position.

The effect of this construction of the valves is that when the valve lifts, the water passes through the valve opening and along the face of the valve practically in a straight 20 line instead of having to take a tortuous passage around the edges of the transverse valves as heretofore. The possibility of chokage by foreign matter is also very much reduced.

25 My arrangement of the leathers also secures a much better fitting of the plunger within the barrel and practically no escape of water from above the plunger.

A further advantage of my improved foot 30 valve is that it is possible by means of the fishing tool illustrated in Fig. 8 to insert or to remove the foot piece E with its valve without raising the pump barrel from the well. The plunger must of course be first 35 removed. This fishing tool comprises a fork W upon the end of a rod or handle, having a catch X pivoted thereto, with a cord Y whereby the catch X may be operated from the top of the well. To insert the foot piece 40 it is placed in the fishing tool as shown in Fig. 8 and lowered down the barrel and screwed into the collar at the foot of the pump. The lug L of the foot piece is shown in section. When it has been screwed home 45 the catch X is withdrawn from beneath the lug L by means of the cord Y and the fishing tool raised. The plunger is then low-

ered into place. To remove a foot piece the fishing tool is lowered to the bottom of the barrel until the fork fits upon the top of the 50 lug L of the foot piece, the catch X is allowed to fall under the lug, and the foot piece may then be unscrewed and raised to the surface.

Where the depth is such as to necessitate 55 the use of a pump rod in sections I prefer to link up the sections by hook and eye joints as shown in Fig. 9 as this obviates the annoyance caused by the breakage of threads.

60 What I claim is:—

In a valve of the class described, the combination with a short tubular member having an opening extending through the bottom thereof and a top wall, the body having 65 a recess disposed obliquely at a sharp angle toward said top portion to provide an oblique seat, the lower end of the seat being provided with an upwardly projecting stud and a shoulder, and the top at its under face 70 being provided with a curved stud projecting therefrom from the upper edge of the valve seating across the water space toward the opposite side of the barrel, and a valve 75 consisting of a flat approximately oval shaped metal back having a face of resilient material such as leather, rubber or softened copper attached thereto to fit closely upon the valve seating, said valve having a notch in the center at the bottom engaging the 80 stud and shoulder to hold the valve centrally relative to the seating and support the valve for rocking movement upon the shoulder, and the top of the valve having a notch engaging the stud at the top to guide the 85 valve in its movement.

In testimony that I claim the foregoing as my invention I have signed my name in the presence of two subscribing witnesses this 2nd day of July 1920.

WILLIAM JAMES NOTT.
